UNITED STATES PATENT OFFICE

HARRY J. MOREY, OF SYRACUSE, NEW YORK, ASSIGNOR TO PASS & SEYMOUR, INCORPORATED, OF SYRACUSE, NEW YORK, A CORPORATION OF NEW YORK

CENTER CONTACT FOR SOCKETS

Application filed March 7, 1925. Serial No. 13,839.

The present invention relates to lamp sockets and more particularly to center contacts for lamp sockets of the key operated type.

5 It is a general object of the present invention to provide a novel and improved form of center contact for lamp sockets.

More particularly it is an object of this invention to provide a one-piece center contact and stationary switch contact for lamp 10 sockets.

Another object of the present invention consists in the provision of a one-piece center contact for lamp sockets which requires no 15 fastening means to retain it in position.

A still further object of the present invention consists in the provision of a one-piece contact for lamp sockets which shall provide resilient contact with the center contact but- 20 ton of a lamp, and which will at the same time provide a stationary member to co- operate with one of the movable switch elements of the socket.

Still another object of the present inven- 25 tion consists in the provision of a stronger bottom insulating button which is not unduly cut away to make room for fastening means for the center contact.

In the accompanying drawing and follow- 30 ing specification, there is disclosed by way of example only, a single modification of the present invention with the understanding however that various changes may be made therein by those skilled in the art in the size, 35 shape, proportion and arrangement of the various parts without departing from the spirit of the invention as set forth in the appended claims.

In said drawing:

40 Fig. 1 is a central vertical section through a lamp socket embodying the improved form of center contact;

Fig. 2 is a partial longitudinal central section taken on line 2-2 of Figure 1;

45 Fig. 3 is a plan view of the blank used in forming the center contact; and

Fig. 4 is a plan view of the lower insulating button with the center contact removed.

In the manufacture of lamp sockets it has 50 long been the aim of manufacturers to reduce

them to extreme simplicity in order that they may function better, have a longer life, be simpler to manufacture and assemble, and be low in cost. To this end the present invention contemplates the combining into one 55 piece of the center contact and one of the stationary switch contacts, the complete elimination of fastening means such as screws, nuts, etc. for holding these parts in position and a simplified method of assembly. 60

There is shown in the drawings a well known form of lamp socket of the key operated type provided with a switch which opens the circuit in two places. This socket comprises the screw shell contact 10, the center 65 contact 11, the lower insulating button 12 and the upper insulating button 13. These two insulating buttons 12 and 13 are suitably secured together by screws not shown, and are provided each with an inwardly facing 70 recess which recesses cooperate to form a switch chamber. The meeting faces of these two members are provided with channels in which is journaled the spindle 14 carrying at its outer end the actuating key (not shown) 75 and on its center the switch operating cam 15 formed of insulating material and having a lost motion connection with the spindle 14 as shown at 16 in order to provide a snap action, as is well known. The upper insulating but- 80 ton 13 is provided with the two movable switch spring contacts 17 and 18 having the lower or stationary-contact engaging portions 19 and 20. The intermediate bowed portions engage the sides of the switch actuating cam 15, as clearly shown in Figure 1. The ends 21 of these spring contacts are se- 85 cured to the upper insulating button by the screws 22 having their heads set in counter-bores, as shown. These screws pass into and 90 have threaded engagement with the tabs 23 on the two circuit terminals 24, containing the binding screws 25 to which the circuit wires leading to the socket are connected so that the two switch springs 17 and 18 are al- 95 ways connected to an electric circuit and are of opposite polarity.

The screw shell contact 10 is secured to the lower insulating button 12 in any suitable manner and is provided with an integral tab 100

26 bent downwardly from the base thereof and projecting through the slot 27 in the lower insulating button in a position to be engaged by the tip 19 of the movable spring contact member 17 when the cam is turned in a position at right angles to that shown in Figure 1 to thus connect the screw shell contact of the socket to one side of the circuit. The wall 28 of the slot 27 provides an abutment against which this tab 26 is pressed in order to insure firm engagement between the parts 19 and 26. The parts thus far described are all old and well known.

The center contact and other stationary switch contact, generally indicated by 11, are formed of one integral piece of spring metal punched or stamped to the shape disclosed in Figure 3 and include the straight central portion 29 having a rounded end 30 provided with the cup-shaped projection 31 which is adapted to engage and contact with the center button on the lamp. The opposite end of this member is provided with the widened portion 32 providing the shoulders 33. This member 11 is adapted to fit in a passage 34 in the lower insulating button which leads from the bottom face thereof into the switch compartment. As shown in Figures 2 and 4, this passage is wider at the top than at the bottom, and is provided with the shoulders 35 where the change in width takes place, which shoulders are adapted to engage with the shoulders 33 on the contact member which is placed in the passage from the upper end thereof so that the greater part of the straight portion 29 projects out below the lower face of the button 12. The widened portion 32 thus remains in the upper portion of the passage in juxtaposition to the tip 20 of the spring contact 18 in exactly similar manner to the relation between the tab 26 and the tip 19 of the switch contact 17 so that upon rotation of the cam to a position 90° removed from that disclosed in Figure 1, electrical contact is made between the tip 20 and the widened end 32 to thus place the center lamp contact in engagement with the other side of the electrical circuit.

The straight portion 29 of the center contact is bent over toward the center of the insulating button 12 around the corner 36 formed by the bottom wall of the button 12 and the inner wall of the passage 34, to the position shown in Figure 1. By being thus bent around the corner 36, the contact 11 is securely held in position against material movement in the passage. Any such movement is further prevented by the overhanging walls 37 at the edges of the widened portions of the passage which however do not project sufficiently over the end 32 of the contact member to be engaged by the movable spring contact 18. The outer wall 38 of the passage provides an abutment against which the end 32 can be pressed by tip 20 when these

two parts contact. In order to secure additional resilience of the center contact to prevent the lamp from jarring out of position, the hole 39 may be punched through the straight portion 29 of the contact just where it bends around the shoulder 38 to reduce the amount of metal at this point and thus add to its resilience.

It will be seen from the above therefore that one of the stationary switch contacts and the center contact is formed of an integral piece of sheet metal which is held in position due to its own shape and the shape of the cooperating passage walls and requires only to be dropped in position and bent over, as shown, for assembly. The face of the lower insulating button 12 is provided with the boss 40 to elevate the center contact above the base of the screw shell contact to serve in positioning the screw shell contact and in positively preventing engagement between it and the center contact.

By providing the above described means for retaining the center contact in position, a stronger bottom insulating button is obtained since it is not cut away or relieved to make room for securing means for the center contact as has been the case in previous forms of sockets. This effectively insures this button against breakage under severe usage.

Having thus described the invention what is claimed as new and desired to be secured by Letters Patent is:

1. In a lamp socket, in combination, an insulating button having a recess opening on one face thereof, said recess being connected to the other face by a passage narrower than said recess, a movable switch contact in said recess, and a stationary contact therein wider than said passage adapted to be contacted by said movable contact, said stationary contact having a narrow part projecting through said passage, bent over the other face of said button to form a center contact and retained in place solely by its cooperation with said button.

2. In a lamp socket, in combination, an insulating button having a recess therein, said recess being connected to one face of said button by a passage, shoulders formed in the walls thereof, a stationary switch member having a contact portion in said recess and abutting said shoulders, a reduced portion integral with said contact portion, passing through said passage and bent over said face of said button to form a center contact, said contact portions cooperating with said shoulders and face to hold said member in position.

3. In a lamp socket, in combination, an insulating button having a recess therein connected to one face thereof by a passage having a common wall with said recess, said slot being wider than said recess for a part of its length and narrower where it opens on said face, a one-piece conducting member, an enlarged

head thereon fitting in the wide portion of said passage and against said common wall and forming a stationary switch contact and a narrow end on said member projecting through said slot and bent over said face to form a center contact.

4. In a lamp socket in combination, an insulating button having a recess therein connected to one face thereof by a passage having 10 a common wall with said recess, said passage being wider than said recess for a part of its length and narrower where it opens on said face, a one-piece conducting member, an enlarged head thereon fitting in the wide portion 15 of said slot and against said common wall and forming a stationary switch contact, and a narrow end on said member projecting through said slot and bent over said face to form a center contact, said member being reduced in strength at said bend to enhance its 20 resilience.

In testimony whereof I hereunto affix my signature.

HARRY J. MOREY.
